BOOKHOLDER

William A. Pinkham, Jr., Fort Worth, Tex.

Application August 19, 1952, Serial No. 21,103

Term of patent 14 years

(Cl. D33—2)

To all whom it may concern:

Be it known that I, William A. Pinkham, Jr., a citizen of the United States of America, residing at Fort Worth, in the county of Tarrant and State of Texas, have invented a new, original, and ornamental Design for a Bookholder, of which the following is a specification, reference being had to the accompanying drawing, forming part thereof.

Figure 1 is an end elevational view of a bookholder embodying my new design.

Figure 2 is a front elevational view thereof, and Figure 3 is a perspective view thereof.

I claim:

The ornamental design for a bookholder, substantially as shown.

WILLIAM A. PINKHAM, JR.
